UNITED STATES PATENT OFFICE.

BERT E. LEAS, OF LUVERNE, MINNESOTA.

RAKE.

Application filed November 1, 1921. Serial No. 512,006.

To all whom it may concern:

Be it known that I, BERT E. LEAS, a citizen of the United States, and resident of Luverne, in the county of Rock and State 5 of Minnesota, have invented a new and Improved Rake, of which the following is a full, clear, and exact description.

My invention relates to a rake, and aims to provide certain new and useful improvements in connection with a device of this character.

More particularly my present invention is in the nature of a rake primarily intended for use on lawns, although the same is not 15 necessarily limited to this particular adaptation.

In connection with rakes of this type, it is well understood that considerable difficulty has been experienced, incident to the 20 fact that leaves, dead grass, etc. have quickly clogged the teeth of the rake, and the operator has had to remove the accumulated débris from the teeth by means of his fingers.

25 Aside from the fact that this operation is more or less objectionable, it also consumes a great amount of time, and with this in mind my present invention aims to provide a rake in which the teeth may be 30 cleaned in a semi-automatic manner, and without necessitating the operator using his fingers to accomplish this result, also overcoming the delay heretofore experienced for the accomplishment of this cleansing of 35 the teeth.

Still another object of this invention is the provision of a device of the character stated which shall be extremely simple in construction and operation, and

40 Still further objects of this invention will appear in the annexed specification, taken in connection with the drawings which latter illustrate one practical embodiment of the same, and in which:

45 Figure 1 is a plan view of a rake embodying my improved construction.

Figure 2 is a sectional side view taken along the line 2—2 and in the direction of the arrows indicated in Figure 1.

50 Figure 3 is a side view of the rake and showing the position which the parts assume upon the teeth being cleaned, and

55 Figure 4 is a transverse sectional view taken along the line 4—4 and in the direction of the arrows indicated in Figure 2.

In these views it will be seen that the ref-

erence numeral 5 indicates the handle of the rake, to which a head of any desirable construction is secured in a manner hereinafter specified. In the embodiment illustrated the head includes teeth 6, all of which extend through a rib 7, the latter serving to retain all of the teeth, as a single unit.

Referring now more particularly to the construction utilized for effecting this attachment it will be seen that I preferably utilize a member terminating in a plurality of forks 8, the rib 7 of the head being disposed between the prongs of these forks, and retained in this position by any convenient means, such as a bolt 9, extending through the prongs. The body of the member aforementioned preferably consists conveniently of a pair of plates 10, arranged one upon each side of the flat outer end portion 11 of the ferrule 12, associated with the handle 5, these portions being held in this position by means of a transversely extending pivot pin 13.

With a view of strengthening the structure, and also to provide means which will serve to limit the rocking movement of the plates 10 with respect to the flat portion 11, it will be noted that the said plates 10 are connected adjacent their rear ends by means 85 of a saddle portion 14, the latter being so disposed as to normally have its inner face contacting with the upper edge portion of the flat portion 11, thus limiting the swinging movement of the plates 10 in one 90 direction.

Finally to limit the swinging movement of the plates in the opposite direction, and also to normally retain these members in their normal position, as in Figures 1 and 95 2, it will be seen first that the rear edges of each of the plates 10 is preferably formed with an off-set part or extension 15 which, when the plates are swung to the position illustrated in Figure 3, contacts with the 100 pin 16 to produce the limitation aforementioned. Also, a spring 17 has its inner end fixedly secured to the under edge of the flattened portion 11, and its outer end engages the lower edges of the plates 10 so that 105 when the parts are moved to the position indicated in Figure 3, said springs 17 will bear against the under edges of the plates 10 and tend to move the same to the position shown in Figures 1 and 2.

110 In operation it will be seen that the head of the rake may be drawn by means of the

handle, through grass, leaves, etc. and that the head of the rake will be retained perfectly elevated with respect to the handle. Assuming, however, that the teeth 6 become choked with dead leaves, and it is desired to clear the same, it will be understood that this may readily be accomplished by an operator simply pushing the rake forwardly as in Figure 3 and when this occurs, the engagement of the rake teeth 6 with the supporting surface will be sufficient to counteract the tension of the springs 17, and cause the head to become immovable with respect to the handle. When this occurs, the teeth 6 forming a part of the head will be moved to a position at which they will lie almost parallel to the supporting surface, and in this position it will be understood that the contact between the supporting surface and the accumulation upon the teeth will be sufficient for the leaves, etc., to be readily stripped from these teeth.

Thus all of the objects set forth in this specification have been accomplished, and it will further be understood that numerous modifications of structure might readily be resorted to without in the least departing from the spirit of my invention; which I claim as;

30 1. A rake including a handle, a tooth supporting head, a pair of plates secured to said head and extending upon opposite sides of the handle, means for rockingly connecting said plates and handle, and a saddle portion connecting said plates and bridging the said handle.

2. A rake including a handle, a tooth supporting head, a pair of plates secured to said head and extending upon opposite sides of the handle, means for rockingly connecting said plates and handle, a saddle portion connecting said plates and adjacent the rear ends of the same, and means carried by said handle and engaging the lower edges of said plates for normally retaining said saddle in contact with said handle.

3. A rake including a handle, a tooth supporting head, a pair of plates secured to said head and extending upon opposite sides of the handle, means extending through said plates and handle for rockingly attaching the same together, a saddle portion connecting said plates and adjacent the rear ends of the same, and a spring having one of its ends attached to said handle its opposite end bearing against the lower edges of said plates whereby to normally retain said saddle in contact with said handle.

4. A rake including a handle, a tooth supporting head, a pair of plates secured to said head and extending upon opposite sides of the handle, means for rockingly attaching said plates and handle together, a saddle portion connecting said plates and adjacent the ends of the same, and a spring having one of its ends attached to said handle its opposite end bearing against the lower edges of said plates whereby to normally retain said saddle in contact with said handle, and extensions to said plates at the rear ends thereof and lateral stops carried by said handle and in the path of travel of said extensions whereby to limit the movement of said plates with respect to said handle.

5. In a device of the character described, in combination, a handle formed with a flattened end portion, a pair of plates rockingly connected with said end, said plates adapted at their front ends to support a rake head, a saddle portion connecting said plates adjacent their rear ends and cooperating with the upper edge of said handle end portion for limiting the rocking movement of the plates in one direction, flexible means for maintaining said plates in normal position, rearwardly projecting extensions at the rear ends of said plates, and lateral stops mounted on said handle in the path of travel of said extensions, whereby to limit movement of said plates in another direction.

BERT E. LEAS.
